CHARLES A. SHULTZ, OF MONTICELLO, INDIANA, ASSIGNOR TO LOCKWOOD & LOCKWOOD, OF INDIANAPOLIS, INDIANA, A FIRM.

CEREAL CLEANER AND SEPARATOR.

Application filed April 19, 1924. Serial No. 707,610.

This invention relates to a machine for cleaning, separating and grading cereals and the like.

The chief object of this invention is to provide in a machine of the character indicated improved means for feeding the cereal material to the improved cleaning and separating mechanism, which in turn feeds the same to a grading construction without intermediate manual handling and with substantially automatic action.

One of the features of the invention consists in the adjustable feeder interposed between the hopper and the cleaning and separating mechanism.

Another feature of the invention consists in the arrangement of the several parts and separating mechanism and also the construction and adjustability of the same.

20 A further feature of the invention consists in the provision of a grading construction into which the cleaning and separating construction is adapted to discharge a part of the contents passing therethrough.

25 One feature of the invention consists in the general arrangement of the several individual mechanisms incorporated therein, whereby the machine may be adjusted for various degrees of separation, dependent upon the cereals to be separated from the cereal material supplied thereto and at a relatively high rate.

The full nature of the invention will be understood from the accompanying drawings and the following description and claims:

In the drawings, Fig. 1 is a side elevational view of a cereal cleaning, separating and grading machine embodying the features of the invention. Fig. 2 is a central sectional view of the machine showing the interior thereof. Fig. 3 is an enlarged plan view showing a portion of one of the separating screens and the agitating means therefor. Fig. 4 is a sectional view of the parts shown in Fig. 3 and is taken on the line 4-4 of Fig. 3 and in the direction of the arrows. Fig. 5 is a sectional view of the parts shown in Figs. 3 and 4 and is taken on line 5-5 of Fig. 4 and in the direction of the arrows.

In the drawings 10 indicates a plurality of upright standard members suitably supported by being provided with base mem-

bers 11 and secured in spaced relation by 55 the upper and lower transverse horizontal frame members 12 and 13 respectively. Intermediate said transverse spacing members is an additional transverse member 14. The side frames formed by the transverse members and the standards support in spaced relation the hopper, the cleaning and separating compartment including the screens, and the grading compartment including the grading screens therein, all in superposed 60 65 relation. In addition to the foregoing compartments, the frame members suitably support the suction fan 15 associated with the cleaning compartment and a second fan or blower 16 associated with the cleaning and 70 grading screens.

In the present embodiment of the invention the hopper compartment 17 is comprised of a pair of side plates 18 suitably secured to the standards 10. The ends of 75 said hopper and the base or bottom are composed of two inwardly and downwardly extending plates or sides 19 and 20. The plate 20 terminates short of the plate 19 and provides an aperture 21 therebetween 80 through which the grain passes from the hopper into the cleaning compartment 22 after passing through a feeding table 9. Interposed in said aperture and suitably secured to the plate 20 as by means of the 85 hinges 23 is a closure plate 24 which is provided with agitating means.

The plate agitating means comprises a bracket plate 25 suitably secured, as in the present instance to the cleaning compartment 22 so as to transmit movement from the same to the closure member 24. Secured to the outer side of the closure member is a pivot support 27 by which a connecting rod 28 is pivotally secured to said closure 90 member. The rod 28 extends through the bracket plate 25 and carries upon its outer end a wing nut 29 for adjustably securing the same thereto. A suitable tension spring 30 is interposed between the outside of the closure member and the bracket plate 95 100 105 25, and in the present instance is concentric with and surrounds the rod 28 to maintain the closure plate in closed position as soon as released from the open position by the movement of the plate 25.

The cereals are supplied to the hopper 17 and discharge through the aperture 21

thereof and are received upon the table 9, which table is provided with suitable sides 8 and a backplate 7. By means of the bolt and wing nut constructions 6, the position of the table 9 can be adjusted to supply grain uniformly throughout the width of the compartment 22, whereas, due to any inclination of the floor, the table normally would discharge to one side of the compartment. Said discharge therefor can be adjusted to secure uniformity of discharge by altering the inclination thereof through the bolt and wing nut constructions illustrated thus generally. An adjustable control plate 26 is also associated with the table and the amount of opening 26^a determines the rate of discharge. Since the table 9 is carried by the compartment 22, it also will be agitated with the agitation of the compartment as hereinafter described.

In the drawings the cleaning compartment 22 is shown pivotally supported upon said frame by means of a pair of links 31, see Fig. 1, pivoted upon the side wall 18 at 32 and pivoted to the compartment 22 at 33 to support said compartment upon the frame. The supporting brackets 34 suitably supported upon the standards 10 and secured thereto, pivotally support at 35^a a rocking lever 35. Said lever is pivotally and suitably connected to the cleaning compartment casing 22 at 36. The rocking levers 35, as shown clearly in Fig. 1, support one end of the compartment while the other end is supported and suspended by the levers 31. In the present instance the pivot 36 upon each side of the compartment is suitably secured in a bracket 137, the same being rigidly secured to an adjusting plate 138. The plate 138 is provided with a longitudinal slot 139 through which the pins 140 extend, said pins being rigidly secured to the compartment wall 22 and being adjustably and rigidly secured in said slot 139 by means of the wing nuts 141. Thus, the angle at which the compartment 22 is supported may be adjusted by means of the plate 138.

When the lever 35 is rocked by suitable means hereinafter to be described, the cleaning compartment as a whole is reciprocated, rocked or cradled, which in turn oscillates the closure member or plate 24 through the rod 28 and about the hinges 23 as a center, and oscillates the feeding table positioned beneath the hopper.

The means for rocking the levers 35 comprises a large driving wheel 40 mounted upon a stub shaft 41 suitably secured to the side frame, and in particular one of the transverse bars 12. As shown in Fig. 1, the stub shaft 41 is adjustably supported upon the machine by means of the rigidly mounted and arcuate supporting bracket 42; the latter being pivoted to the transverse member 12 at 43 and being adjustably and rigid-

ly secured thereto at 44 by any suitable means. The driving wheel 40 is provided with a pulley portion 45 by which said wheel is turned. The driving wheel 40 is provided with a toothed periphery 47 and a sprocket chain 48 is driven thereby, which in turn drives a sprocket pinion 49 rigid with the shaft 50, see Fig. 2, suitably supported upon the framework. The sprocket pinion 49 carries the eccentric pin 51, which in turn supports the eccentric, crank arm, pitman or lever 52, the other end of which is connected to the depending end of the lever 35. The shaft 50 extends entirely across the machine and upon each side of the same is positioned one of the levers 52 which rocks the respective lever 35. If desired, the power pulley 45 may be removed and replaced by a crank and eccentric so that the machine may be hand-operated.

Within the cleaning compartment 22 is secured a plurality of cleaning members in spaced relation with each other and inclined at an angle to the horizontal. The cleaning members are also offset from each other in such a manner that each succeeding member extends downwardly and beneath the upper or superposed member. In the present instance the cleaning members are so formed that the same are seatable one upon the other and may be readily removed from the compartment or from the remaining members. Likewise, the members are all interchangeable. Furthermore, the members are readily detachable so that all that is necessary to separate the particular types of grains or cereals from the general mixture, is to position in the compartment 22 the particular set of cleaning members. This will be readily understood for example when it is desired to separate from one mixture oats, and at another time to separate from the mixture wheat, the screens for each product will vary having the necessary requirements to secure the desired separation.

The compartment 22 supported as previously described is provided with an inclined forward face 53. A chute member 54 communicates with the compartment 22 through an opening 55 at the free end thereof and is suitably secured thereto by means of the wing nuts 55^a. Within the aperture 55 is a second opening or aperture 56 which communicates with the suction blower or fan 15, the latter being provided with a discharge or exhaust conduit 57. The fan member 58 within the blower is rotated by means driven from the wheel 40, and said fan member sucks and separates the dust and chaff from the grains, the lighter particles thereof passing through the fan 15 and out through the exhaust conduit 57, while the heavier particles thereof collect at the bottom of the compartment 22 and discharge therefrom by means of the chute 54.

There is thus secured a multiple selection, the intermediates being retained in the machine, the lighter and the heavier particles being discharged therefrom. The compartment 22 is also provided with a grain discharging aperture 46 adjacent the aperture 55 and separated therefrom by the cleaning means as shown in Fig. 2. The cleaning and separating means contained within the compartment 22 consist essentially of separating screens. These screens are not only loosely positioned therein, but also are positioned as previously stated in superposed relation and in offset relation as shown clearly in Fig. 2. Each of the screening means, see Figs. 3 to 5 inclusive, comprises a substantially rectangular frame formed by a pair of parallel bars 60 connected by a pair of transverse bars 61. To the framework 60-61 is suitably secured a suitable sheet of screening 62. The same is provided with a plurality of perforations 63 in gang or group formation, as shown most clearly in Fig. 4, which gang formations are in spaced relation with each other. Upon the lower inclined end of each rectangular frame is suitably secured a transverse block or blocks or bar 64, see Fig. 2. The lower or superposed screening plate formed by the square frame and the screening sheet is provided with a pair of aligned notches 65 adapted to receive a block 66 which supports the lowermost screening plate within the compartment 22 and secures the same against longitudinal movement within said compartment. The remaining superposed screening above the lowermost screening plate is supported in turn by the member 60 on the next lower plate and is limited in downward or longitudinal movement thereon upon the inclined surface thereof by the transverse blocks or bars 64 secured to the lower end of each of the screening plates.

Upon the outer and herein illustrated inclined side or face 53 of the compartment 22 is secured a plurality of deflector plates 67, said plates being in parallel relation with each other and extending inwardly within the compartment and downwardly at an angle greater than the inclination of said plates. Since in the present instance the transverse bars 61 provide an aperture 68 between each of the superposed screening plates, the deflector plates project into the same and convey the grain and similar material discharged from the upper edge of each of said screening plates into the next succeeding screening plate. This construction prevents the direct discharge of grain and the like into the base of the compartment 22 and through the outlet 46.

Means cooperating with the screening plates to effectively separate the chaff from the grain comprises a plurality of transverse "teasing" or agitating strips 69, said

strips being secured in spaced relation with each other by means of a plurality of parallel and yielding strips 70. As shown clearly in Figs. 3, 4 and 5, the strips 69 overlie the screening plate 62 and each has a beveled edge 69a. The strips 70 may be of any suitable material, and leather has been found quite satisfactory. A turtle back 71 is suitably secured to the strips 70 and bridges the gap between the strips 69, so that any grain which travels upon the top of the strip 69 or the strip 70 or passes from the former to the latter and attempts to jump the gap by riding on the strip 70, will be deflected into the space between the teasing strips 69. The grain is thereupon forced beneath the teasing strip or plate 69, and if small enough will pass through the perforations 63 in the screening plate and be discharged upon the next lower screen, whereupon the process will be repeated. Those grains which are too large will ultimately be discharged outwardly through the chute 54. As shown clearly in Figs. 3 and 4, the perforations, which are grouped and in spaced relation with each other, are substantially covered by the teasing strips at all times. The imperforate portions are normally uncovered and exposed between strips 69.

In the present instance a spring member 73 is shown secured to a hook or adjustable bolt 74 which carries a nut 72 and another nut 72a. The foregoing construction provides that the initial or normal position of the skeleton or teasing framework constructed as aforesaid can be adjusted with respect to the perforations 63 by means of the bolt and nut construction 74-72 and 72a. Also, the skeletonized teasing construction is thus yieldingly supported adjacent said perforated plate 60 through the medium of the spring 73. If desired, a plurality of said springs 73 may be substituted for the single spring 73 herein illustrated without departing from the broader feature of the invention. A closure or box 74a encloses the projecting ends of the bolts 74 and through this means the position may be adjusted. This box also provides a suitable receptacle for tools and the like that may be required for the machine.

From the foregoing construction it will be understood that the cleaning and separating compartment 22 is reciprocated by the levers 35 and the individual screens 62 also reciprocated within said compartment, due to the motion of the same. Furthermore, since each of the skeletonized "teasing" means adjacent each screening plate is yieldingly attached to the reciprocating wall of the compartment 22, said teasing means will have a slightly independent reciprocatory motion upon said screening plate 62, and said reciprocatory motion may or may not be at

the same period as the reciprocations of said screening plates and the compartment, and generally will not. Grain which is discharged from the hopper through the aperture 21 is received by the table 9 and discharged therefrom on to the uppermost inclined and offset screening plate. The grains gradually work their way, due to the angle of the "teasing" means as illustrated in Fig. 4, beneath the strips 69, and then work down beneath the same until they register with one of the openings 63, through which they drop upon the next succeeding screening plate, where the same operation is repeated. The "teasing" members by rubbing upon the individual grains clean and separate the same from portions of the chaff, dirt and the like. The suction fan 58 separates this chaff and lighter dirt particles from the grains during the operation of successive separations through the passage of the grains through the successive screens.

The screened and partially winnowed grain is collected from beneath the lowermost screening plate, since the screening plate and the bottom of the compartment 22 are inclined at an angle to the horizontal. It will be remembered that the lower end of the compartment 22 has an aperture 46, and adjacent said aperture there is herein illustrated, see Fig. 2, inclined guide or deflecting plate 75, which discharges grain and the like into a hopper 76 therebeneath. This hopper is formed by the side walls 77, the inclined receiving wall 78 and the hinged rear wall 79. The grain thus passes through the hopper by means of the aperture 80 formed between the plates 78 and 79 on to a spring plate 81 positioned therebeneath. This plate directs the grain from said plate to a winnowing plate 82. The winnowing plate is provided with flanges 83 by which the same is pivotally and adjustably supported by the pins 84 secured to the side plates 77. Thus, the angle of the winnowing plate may be adjusted as desired.

Positioned beneath an extension of the plate 81 is a plate 86. Said plates together with the extensions of the side plates 77, form a conduit which is adapted to discharge air under pressure adjacent the winnowing plate 82, and this air passes through the grains and the like which discharge upon the winnowing plate. Herein the fan 81^a is shown adapted to provide the air blast, and as previously indicated, said fan is driven from the common source of power.

The separating and grading compartment 87 is pivotally supported similar to the manner of supporting the cleaning and supporting compartment 22. In the present instance the pins 88, see Fig. 1, are rotatably supported in the transverse bearing members 14 and to each of said pins is secured a

depending supporting lever 89 provided with a longitudinal slot 90 by which said lever is adjustably secured to said pin by means of a wing nut 91. The other end of said lever is provided with an inwardly extending bracket in which is pivotally supported a pin 93 secured to said compartment. Thus a link arrangement similar to linkage 31-32-33 is secured. The opposite end of said compartment 87, see Fig. 1, is also pivotally supported by means of the pins 94 rotatable in suitable bracket means carried by the ends of the levers 35. Thus, when the pitman 52 is reciprocated by the means previously described, the compartment 87 will also be reciprocated simultaneously and in timed relation with the compartment 22. The speed at which the grains will pass through the tilted compartment 87 is partially dependent upon the angle in which said compartment is adjustably secured, as well as the rate of reciprocation.

Reference will now be had particularly to Fig. 2. The compartment 87 comprises a pair of spaced screens 96 and 97, said screens 96 being of different mesh such that the first screen separates the larger sized grains from those of the middle and smaller sizes; while the second screen positioned beneath separates the middle sized grains from the smaller sized grains, the latter passing through both screens. The screen 96 discharges the larger sized grains into a receptacle 98, the same having an inclined bottom so as to discharge the grain collected therein to one side of the machine. Similarly, the receptacle 100 is adapted to receive through the opening 102 the middle sized grains which have been separated by the screen 97. This receptacle is provided with an oppositely inclined bottom, so that it discharges the collected grain at the opposite side of the machine, but at the same end. The compartment 87 is also provided with a bottom plate 104, said plate having an aperture 205 near the lower end thereof. Through this aperture all the grain which passes through the screens 96 and 97 is discharged and may be collected in a suitable receptacle positioned therebeneath.

In addition to the means for reciprocating the compartment 87 previously described, means are provided adjacent said compartment for agitating the grains passing therethrough. Said means is shown most clearly in Figs. 1 and 2 and comprises a pair of bracket members 107 stationarily secured to the frame. In each of said bracket members is pivotally supported the lever 108, the same carrying on one of its ends a beater or agitator bar member 109 which extends transversely of said compartment 87 adjacent the bottom plate 84. The means for causing said bar to move upwardly and engage or strike the bottom plate 104

comprises a spring 105 having an adjustable connection 106 with the frame construction. Means for depressing the beater bar 109 so that the same will rise upwardly when released, due to the influence of the springs 105 for striking a blow upon the bottom plate 104, thereby agitating the grains upon the screens contained within the compartment 87, is as follows: A shaft 114 extends transversely of the machine and is rotatably supported in bearings 115 suitably secured to the transverse bars 13. Upon the shaft 114 and rotatable therewith is a rotatable finger 117 for engaging the free and larger end of the lever 108, thereby elevating this free end of the lever and depressing the opposite end in opposition to the spring 105. Means for rotating the shaft 114 comprises a sprocket wheel, not shown, substantially similar to the sprocket wheel 49 and oppositely positioned upon the shaft 50. A chain or similar construction 120 rotates a sprocket gear 121 which is carried upon the shaft 114.

The operation of the machine has been simultaneously described with the description of the parts thereof so that a résumé of the operation will suffice to understand the same. The grain which is to be cleaned, winnowed, separated and graded is discharged into the hopper 17 and is discharged therefrom past the agitating closure at the base of said hopper into the reciprocating, cleaning compartment. The grain passes through the several superposed cleaning and separating screens by the action of the "teasing" or agitating strips. The grain finally passes through all of said screens and collects in the lower portion of the cleaning compartment from whence it is discharged into a winnowing hopper where the remainder of chaff, dirt and the like is removed from the clean grains. The clean grain is discharged from the the winnowing device into the grading compartment where it is separated by suitable screening into a plurality of sizes, in the present instance three being shown.

The machine as constructed simultaneously reciprocates the cleaning compartment and the grading compartment, as well as actuates the agitating plate and bar adjacent the hopper discharging aperture and actuates the beater bar adjacent the reciprocating grading compartment.

While the invention has been described in detail, it will be understood that many modifications thereof are possible, a few of which have been suggested herein and others of which will suggest themselves to those skilled in the art, but it will be understood that all of the foregoing modifications are considered within the purview of this invention.

The invention claimed is:

1. In a cereal cleaning machine, the com-

bination with a fan, and a closed compartment adjacent thereto and communicating therewith including an imperforate bottom, of a discharge outlet near the lowest end of said bottom for the separated cereal grain, 70 a second discharge outlet adjacent but spaced from the former for the longer and refused particles, a third discharge outlet adjacent thereto for the lightest particles and connecting said compartment with said fan, and grain separating means in the compartment separating the grain discharge outlet from the other outlets. 75

2. In a cereal cleaning machine, the combination of a compartment, a plurality of superposed screens positioned in parallel relation with said compartment, a teasing construction lying on each screen and yieldingly connected to the compartment, said screens being positioned one above the other and loosely related, and means for securing the lowermost screen to the compartment, whereby all of the superposed screens will be successively secured in the aforesaid relation. 90

3. In a cereal cleaning machine, the combination of a compartment, a plurality of superposed screens positioned in parallel relation with said compartment, a teasing construction lying on each screen and yieldingly connected to the compartment, said screens being positioned one above the other and loosely related, means for securing the lowermost screen to the compartment, whereby all of the superposed screens will be successively secured in the aforesaid relation, and adjustable means associating each teasing construction with the compartment. 95

4. In a cereal cleaning and separating machine, the combination of a compartment, a plurality of superposed screens inclined to the horizontal within said compartment, means for similarly offsetting each superposed screen, and individual plate means interposed between adjacent screens adjacent the upper inclined edge of one of said superposed screens and independent thereof and secured to the compartment for deflecting the grains discharged over said screen upon the next succeeding lower screen. 105

5. In a cereal cleaning and separating machine, the combination of a compartment, a plurality of superposed screens inclined to the horizontal within said compartment, means for offsetting the next superposed screen, individual means interposed between adjacent screens adjacent the upper inclined edge of the upper screen for deflecting the grains discharged over said screen on to the next succeeding lower screen, a teasing construction lying on each screen, and yielding means associated with each of the teasing constructions for yieldingly supporting the same within the compartment. 120

6. In a cereal cleaning and separating ma-

chine, the combination of a compartment, a plurality of superposed screens inclined to the horizontal within said compartment, means for offsetting the next superposed screen, individual means interposed between adjacent screens adjacent the upper inclined edge of the upper screen for deflecting the grains discharged over said screen on to the next succeeding lower screen, a teasing construction lying on each screen, yielding means associated with each of the teasing constructions for yieldingly supporting the same within the compartment, and an adjustable connection associated with said yielding means.

7. In a cereal cleaning and separating machine, the combination of a reciprocatory separating compartment, a plurality of inclined superposed separating screens therein, each screen being offset from the adjacent screen, a teasing construction on each screen including a plurality of teasing strips in spaced and parallel relation and hugging each of said screens, each strip having an upturned edge for receiving grain and forcing the same between the strip and the screen, and yielding means for securing agitation of the strips relatively of the screens.

8. In a cereal cleaning and separating machine, the combination of a reciprocatory separating compartment, a plurality of inclined superposed separating screens therein, each screen being offset from the adjacent screen, a plurality of teasing strips in spaced and parallel relation and hugging each of said screens, and each strip having an upturned edge for receiving grain and forcing the same between the strip and the screen, means for agitating the strips independently of the screens, and individual means interposed between each of the upper ends of adjacent screens for insuring that all of the material separated by the compartment will pass from one end of the upper screen through one or more intermediate screens to the opposite end of the lower screen.

9. In a cereal cleaning machine, the combination of a compartment, an inclined separating screen therein, a plurality of teasing strips in spaced and parallel relation and hugging said screen, each strip having an upturned grain-engageable edge for forcing the grain between said strip and the screen, transversely positioned means connecting said strips in the aforesaid relation, and deflecting means associated with each of the transverse connecting means in juxtaposition to the spacing between said strips for deflecting grain riding upon said connecting means into the spacing between said strips.

10. In a cereal cleaning machine, the combination of a compartment, an inclined separating screen therein, a plurality of teasing

strips in spaced and parallel relation and hugging said screen, each strip having an upturned grain-engageable edge for forcing the grain between said strip and the screen, transversely positioned flexible means connecting said strips in the aforesaid relation, and deflecting means associated with each of the transverse connecting means in juxtaposition to the spacing between said strips for deflecting grain riding upon said connecting means into the spacing between said strips.

11. In a cereal cleaning machine, the combination of a compartment, an inclined separating screen therein having a plurality of openings therethrough in grouped and spaced relation, a plurality of teasing strips in complementary spaced relation and hugging said screen, each strip having an upturned grain-engageable edge for forcing the grain between said strip and the screen, each strip being positioned immediately above a group of perforations and normally covering the same, transversely positioned means connecting said strips in the aforesaid relation, and deflecting means associated with each of the transverse connecting means in juxtaposition to the spacing between said strips for deflecting grain riding upon said connecting means into the spacing between said strips.

12. In a cereal cleaning machine, the combination of a compartment, an inclined separating screen therein having a plurality of openings therethrough in grouped and spaced relation, a plurality of teasing strips in complementary spaced relation and hugging said screen, each strip having an upturned grain-engageable edge for forcing the grain between said strip and the screen, each strip being positioned immediately above a group of perforations and normally covering the same, transversely positioned flexible means connecting said strips in the aforesaid relation, and deflecting means associated with each of the transverse connecting means in juxtaposition to the spacing between said strips for deflecting grain riding upon said connecting means into the spacing between said strips.

13. In a cereal separator, the combination of a supporting frame, a hopper positioned forwardly upon the same, a cleaning compartment adjustably and oscillatably supported by said frame in inclined position with its lower end positioned beneath the hopper, a separating and grading compartment adjustably and oscillatably supported but oppositely inclined, means for simultaneously oscillating both compartments, a plurality of discharge outlets in each compartment, the outlets of each compartment being positioned at the lower ends, whereby the cleaning compartment will discharge the cereals rearwardly and the grading com-

partment will discharge the cereal forward-
ly at the same end that the grain is supplied
to the machine, means for agitating the
grain in the cleaning compartment in its
5 passage therethrough, and other means for
agitating the grain in the grading compart-
ment in its passage therethrough.

14. In a cereal separator, the combination
10 of a supporting frame, a hopper positioned
forwardly upon the same, a cleaning com-
partment adjustably and oscillatably sup-
ported by said frame in inclined position
with its lower end positioned beneath the
15 hopper, a separating and grading compart-
ment adjustably and oscillatably supported
but oppositely inclined, means for simulta-
neously oscillating both compartments, a
plurality of discharge outlets in each com-
20 partment, the outlets of each compartment
being positioned at the lower ends, whereby
the cleaning compartment will discharge the
cereals rearwardly and the grading com-
partment will discharge the cereal forward-
25 ly at the same end that the grain is supplied
to the machine, a table adjustably mounted
and interposed between the hopper and the
cleaning compartment for securing uni-
formity of discharge to the latter across the
30 compartment, a plate interposed between the
compartments, and a blower fan discharg-
ing adjacent said plate for additional clean-
ing.

15. In a cereal separator, the combination
35 of a supporting frame, a hopper positioned
forwardly upon the same, a cleaning com-
partment adjustably and oscillatably sup-
ported by said frame in inclined position
with its lower end positioned beneath the
40 hopper, a separating and grading compart-
ment adjustably and oscillatably supported
but oppositely inclined, means for simulta-
neously oscillating both compartments, a
plurality of discharge outlets in each com-
45 partment, the outlets of each compartment
being positioned at the lower ends, whereby
the cleaning compartment will discharge the
cereals rearwardly and the grading com-
partment will discharge the cereal forward-
50 ly at the same end that the grain is supplied
to the machine, means for agitating the
grain in the cleaning compartment in its
passage therethrough, other means for agi-
tating the grain in the grading compart-
55 ment in its passage therethrough, an air de-
flecting plate interposed between the com-
partments, and engageable by the grain in
passing from one compartment to the other
and a blower fan discharging adjacent said
60 plate for additional cleaning.

16. In a cereal cleaning machine, the com-
bination of a supporting frame, a hopper
positioned forwardly of the same, a cleaning
compartment positioned therebeneath, a
grading compartment positioned beneath
65 said cleaning compartment and movably
supported by the frame, said compartments
being oppositely inclined, the lower end of
the former discharging into only the upper
end of the latter, the lower end of the
70 former also having a waste discharge, a suc-
tion device associated with said waste dis-
charge, a blower device associated with the
discharge from the former compartment to
the latter compartment, means in the clean-
75 ing compartment for separating the larger
grains from the smaller grains and wasting
the former in addition to the lighter parti-
cles by the suction means, the discharge
from the blower device separation and that
80 of the larger grains being separated and
independent, and means for agitating the
grading compartment in addition to move-
ment on the frame for securing a grading
of the cleaned and smaller grains.

In witness whereof, I have hereunto
affixed my signature.

CHARLES A. SHULTZ.
